UNITED STATES PATENT OFFICE.

EDWARD ABERLE, OF WEST NUTLEY, NEW JERSEY.

LOOSE-LEAF BINDER.

Substitute for application Serial No. 129,746, filed October 26, 1916. This application filed April 14, 1922.
Serial No. 552,590.

To all whom it may concern:

Be it known that I, EDWARD ABERLE, a citizen of the United States of America, and a resident of West Nutley, county of Essex, State of New Jersey, have invented certain new and useful Improvements in Loose-Leaf Binders, of which the following is a specification.

My invention relates to loose-leaf binders and has for its object to provide a simple construction in which the leaves are readily inserted in and removed from the binder, and in which said leaves are efficiently maintained in position therein. Other objects of my improvement will appear from the description hereinafter and the features of novelty will be pointed out in the appended claims.

In the accompanying drawings, which illustrate several examples of my invention without defining its limits, Figure 1 is a plan view showing one form of my improvement in an open position; Fig. 2 is a similar detail view partly in section; Fig. 3 is a fragmentary, sectional view on an enlarged scale taken on the line 3—3 of Fig. 1; Fig. 4 is a fragmentary section also on an enlarged scale on the line 4—4 of Fig. 1; Fig. 5 is a perspective view of one of the binder elements; Fig. 6 is a plan view, with parts broken away, illustrating a further form of my improvement; Fig. 7 is a sectional view, on an enlarged scale, partly broken away and taken on the line 7—7 of Fig. 8; Fig. 8 is a detail edge view thereof; and Fig. 9 is a perspective view of a binder element included in this form of my invention.

As shown in Figs. 1 to 5 inclusive, my improvement comprises a pair of retaining members 15 arranged in alignment with each other and provided with recesses 16, the open ends of which point inwardly toward each other, as shown in Figs. 1 and 2. In the preferred arrangement, the bottom walls of the retaining members 15 are extended toward each other either into contact or close proximity, or said members are connected by means of a continuous member *a* which forms the bottoms thereof and extends between the same. With either of the above arrangements, the formation of objectionable shoulders which might interfere with the ready operation of the device

is avoided. The retaining members 15, and their extended bottoms or continuous member *a*, are secured upon a suitable support 17 in any convenient manner, as by gluing or by means of rivets 18 whereby the said members are maintained in their proper locations and in proper operative position. In most cases, the support 17 comprises a protective cover which is connected by means of a back 19 with a second protective cover 20, as shown in Fig. 3; the back 19 may be free from or suitably connected with the members 15, it being understood that the cover 20 is free to hinge upon said back 19 at the point *b* whereby said cover 20 may be swung to the open position shown in Fig. 1. The said cover 20, in addition, may be scored, as indicated at *c*, or otherwise constructed so as to be capable of a swinging movement about this point also. The form of my improvement being described further includes a plurality of binding members or strips 21 constructed of tough paper or of any other suitable material capable of being readily flexed; said strips 21 preferably having reduced ends 21^a whereby shoulders 21^b are formed, the purpose of which will appear more clearly from the description hereinafter. Each strip 21 carries a flap 22 which extends beyond the longitudinal edge 21^c of the strip and is covered either on one or both surfaces with mucilage or other adhesive, the said flaps 22 serving as a means whereby the leaves 23 are operatively combined with the strips 21, as will also be more fully pointed out hereinafter.

In their operative positions, the strips 21 are superimposed upon each other and extend between the retaining members 15 into the recesses 16 from which the reduced ends 21^a project, as shown in Figs. 1 and 2, the distance between the shoulders 21^b of each strip 21 being approximately equal to the distance between the opposed ends of the retaining members 15. With this arrangement, the shoulders 21^b will practically engage the said open ends of the retaining members 15 and will thus prevent any substantial movement of said strips in the direction of their length relatively to the members 15 and consequently will prevent an unintentional removal of the ends 21^a from said members 15. In addition to the elements so far described, this form of my in-

vention may include a clamping member 24 which may be constructed of any suitable material capable of being flexed, and when used, is located upon the uppermost strip 21, with its ends positioned in the recesses 16 of the retaining members 15. This clamping member 24 exerts a pressure upon the plurality of strips 21 tending to clamp them firmly in position, it being understood that said clamping member 24 may be omitted and replaced by one or more strips 21 to completely fill the recesses 16 in a vertical direction.

In utilizing this form of my improvement, the leaves 23 are pasted upon the flaps 22, either one or both surfaces of the projecting portion of each flap being used for this purpose, as desired. In the preferred form, only the upper surface of each flap is utilized, in which case the edge 21^c of each strip 21 will serve as a guide against which the edge of the leaf 23 may be placed to properly position the said leaf with respect to the particular strip with which it is connected. The attaching of the leaves may be readily accomplished by first simply moistening the flaps 22 or the edge of the leaf to be attached and then pressing the one edge of the leaves thereon, and may be facilitated by removing the complete series of strips from the retaining members 15 as a unit. This may be readily accomplished by simply flexing said strips 21 sufficiently to remove the ends 21^a from the recesses 16, it being understood that the clamping member 24, if it forms part of the arrangement, is also removed in a similar manner.

After the leaf or a plurality of leaves has or have been attached to the strips, the whole series, including those which have been connected with the leaves, are returned to their operative positions, which may be readily accomplished by first inserting one end of the series into one recess 16, and then flexing the whole sufficiently to permit the other end to be inserted into the other recess 16. The insertion of the ends of the strips into the recesses 16 is facilitated by the extended bottoms or the continuous member *a* of the retaining members 15, as will be obvious. The resiliency or tendency of the strips 21 to straighten out will properly position the ends 21^a in the recesses 16 as soon as the strips are freed from restraint or permitted to reflex. If the clamping member 24 is used, it may also be returned in place above the series of strips 21 in a similar manner. It will be understood that the described method of removing and returning the series of strips as a unit is only an example and that the said strips may be manipulated singly, in groups, or otherwise, if this is preferred. It will be further understood that in all cases the recesses 16

are filled to capacity either with strips 21 alone, or with a series of said strips, plus the clamping member 24, so that said strips are at all times firmly held in operative combination with the retaining members 15, and yet are readily removable therefrom either individually, in groups, or collectively as a unit. The leaves 23 are firmly secured in position at all times, without regard to whether all of the strips 21 are attached to leaves or whether only one or several of said strips are so attached; in the latter case, the unused strips act as fillers to maintain all of the strips in operative position. The flaps 22, in addition to serving as a means for connecting the strips and leaves, also act as hinges upon which the said leaves may be readily and conveniently turned.

It will be apparent that, if desired, the shoulders 21^b may be omitted and the strips 21 made of even width throughout, in which case said strips are preferably made of such length as to substantially fit between the inner end walls of the recesses 16 to prevent any substantial lengthwise shifting of said strips in the retaining members 15. This latter is, of course, not absolutely necessary, as the recesses 16 may simply be made sufficiently deep, so that even if said strips are capable of considerable lengthwise movement, this will never be sufficient to unintentionally remove the ends of said strips from said recesses. It will also be obvious that the strips may each be combined with two leaves formed by folding a single sheet of material upon itself, the flaps 22, in this instance, being connected with one side of said fold and the fold serving as a hinge for one leaf thereof.

In Figs. 6 to 9 inclusive, I have illustrated a construction whereby the capacity of the binder may be adjusted to meet varying conditions and in which waste space is obviated or at least maintained at all times at a minimum point. As shown by way of example in said Figs. 6 to 9, the arrangement comprises a pair of main retaining members 15^c constructed in substantially the same way as in Fig. 1 and provided with recesses 16^b, the open ends of which point inwardly toward each other, as illustrated in Fig. 7. The said main retaining members 15^c may be rigidly fastened upon a support or protecting cover 17^a, or they may be detachably secured thereto, as will be more freely described herein-after, and in any case are connected in the form of a unit by means of a connecting member 19^a, preferably comprising a right-angled strip of metal or other suitable material extending between said main retaining members 15^c and forming the backs and bottoms thereof. The said connecting member 19^a projects upwardly beyond said re-

taining members 15^c and is turned inwardly to form a flange 19^b which extends throughout the length of said connecting member 19^a, as shown in Fig. 7. The main retaining members 15^c are further provided with upright projections 25 bent at substantially right angles at their upper portions to form flanges 26, the flange 19^b and the flanges 26 projecting toward each other, as shown in Fig. 8. The arrangement now being described further includes auxiliary retaining members 15^d having recesses 16^b and corresponding to the main members 15^c, said auxiliary retaining members 15^d, as shown in Fig. 9, being similarly connected in the form of a unit by means of a connecting member 19^e forming the backs and bottoms of said auxiliary retaining members and which extends above said auxiliary members 15^d, the projecting portion being formed with a flange 19^d corresponding to the flange 19^b. The said auxiliary retaining members 15^d are also provided with upright projections 25^a and flanges 26^a located and arranged in the same way as are the projections 25 and flanges 26 of the main retaining members 15^c. In addition, the auxiliary retaining members 15^d are provided with depending projections 27 formed with continuing flanges 28, the latter projecting outwardly or away from each other, as shown in Figs. 8 and 9. In the preferred arrangement, the projections 27 are so located on the auxiliary retaining members 15^d as to readily fit between the flanges 19^b and 26 or 19^d and 26^a, while the distance between the flanges 28 and the bottoms of the auxiliary retaining members 15^d is such that the flanges 19^b and 26 or 19^d and 26^a will fit therein, as will more fully appear hereinafter. The projections 25 and flanges 26 of said main retaining members 15^c and the projections 25^a and flanges 26^a, together with the projections 27 and flanges 28 of the auxiliary retaining members, may be constructed in any suitable manner and preferably are formed as integral elements of the respective retaining members by cutting and shaping portions of the latter, as shown in Fig. 9.

A second protecting cover 20^a is also included in the present form of my improvement and may be detachably secured in operative position, as will be more fully described hereinafter, in any suitable manner, as by being provided with a locking member 29 secured to the cover 20^a by rivets 30 or otherwise. The member 29 is fastened to the inside of the cover 20^a in such a manner as to leave the opposite end portions 29^a free to form resilient attaching means and is preferably, though not necessarily, formed with shoulders 29^b, the purpose of which will appear more clearly further on in the description.

It will be understood that the method of connecting and disconnecting the leaves in the form now being described may be the same as in the forms of my improvement previously described.

If the main retaining members 15^c and connecting members 19^a are constructed in the form of a unit separate from the cover 17^a, any suitable means may be provided for detachably securing said unit to said cover as, for instance, by providing a bolt 31 which passes through suitable openings 32 and 33 in solid portions 16^c of said retaining members 15^c and in the cover 17^a respectively, as shown in Figs. 7 and 8, and is secured by a nut 34 which screws upon the projecting end of said bolt and firmly clamps said unit to said cover. It will, of course, be understood that the bolt 31 is of a proper length to produce this result. In this case, the leaves 23 may be detachably connected with the main retaining members 15^c either before or after the latter have been attached to the cover 17. It will, of course, be understood that said retaining members 15^c may be rigidly connected with the cover, if this should be preferred. If the capacity of the main retaining members 15^c is sufficient to accommodate the number of leaves desired in a particular instance, then the protecting cover 20^a may be attached in position by springing the ends 29^a of the locking member 29 into said retaining members, as will be apparent from Fig. 7. It will be understood that when so attached, the cover 20^a will rest upon the flanges 19^b and 26 and will not interfere with or be interfered with by the bolt 31, the head of the latter being located between the flanges 19^b and 26 and lying entirely below the same. In this case, the binder will comprise the main retaining members 15^c and the two covers 17^a and 20^a, the back of the binder being formed by the connecting member 19^a and will form an absolutely complete device.

If it is desired to increase the capacity of the binder, a second unit comprising a pair of auxiliary retaining members 15^d and a connecting member 19^e is combined with the first unit consisting of the main retaining members 15^c and connecting strips 19^a. The second unit may be readily and firmly connected with the first unit by simply passing the projections 27 between the flanges 19^b and 26 and sliding the flanges 28 beneath said flanges 19^b and 26, as shown in Fig. 8, it being understood that the cover 20^a is first removed by detaching the ends 29^a from the main retaining members 15^c. The second unit may be secured against sliding movements in the direction of its length relatively to the first unit in any suitable manner. For instance, the auxiliary retaining member 15^d may be provided with openings 32^a arranged to register with

the openings 32 and 33 of the main retaining members 15^a and cover 17^a, respectively, and bolts 31 may be passed therethrough and secured by means of nuts 34 whereby said units are firmly clamped together. In this case, the bolts 31 will be somewhat longer than the bolt 31 previously referred to. If the additional capacity secured with the addition of the second unit is sufficient, 10 the cover 20^a may be attached in position by inserting the ends 29^a of the locking member 29 into the recesses 16^b of the auxiliary retaining members 15^a whereby the binder is again complete and now includes two 15 units.

If the capacity of the binder is still insufficient for the intended purpose, a third unit, composed of auxiliary retaining members 15^a and their connected and co-operating parts, may be added upon the second unit. This may readily be accomplished by first again detaching the cover 20^a and removing the bolts 31 and then passing the projections 27 of the third unit between the flanges 19^a and 26^a of the second unit and sliding the flanges 28 of said third unit beneath said flanges 19^a and 26^a of the second unit. The combined units may again be secured against separation by passing bolts 31 of suitable length through the openings 32^a, 32 and 33 and fastening said bolts in position by means of the nuts 34 to firmly clamp the group of units together. Additional capacity may be secured by adding 35 additional units in the described manner, said units being, in all cases, clamped together against separation by bolts 31 of proper length and co-operating nuts 34, the cover 20^a in each case being detachably connected with the retaining members of the final unit 15^a.

It will be seen that the retaining members of each succeeding unit rest upon the flanges of the preceding unit and that the upright portions of the connecting members 19^a and 19^c, together, form a substantially continuous back for the binder at all times, while the horizontal portions of said members 19^c are located between adjacent 50 units, the horizontal portion of the member 19^a resting upon the cover 17^a. Similarly, the cover 20^a rests upon the flanges 19^a and 26^a of the final or terminal unit, while the head of the bolt 31 is always located between 55 said flanges of said terminal unit and thus does not interfere with the positioning and proper location of said cover 20^a.

It will be readily apparent that a binder of any capacity may be constructed in a simple manner with this form of my improvement and that said binder may at all times be maintained at a capacity in which unused space is kept down to a minimum point and in which the elements of bulkiness and difficulty in handling, due to the

presence of such waste space oftentimes present in binders of relatively large, fixed capacity, are avoided.

The covers 17^a and 20^a are both preferably scored as indicated at 35, or otherwise 70 constructed to provide for the proper manipulation thereof to and from an open position. The shoulders 29^b of the locking member 29, in co-operation with the retaining members, at all times and whatever the 75 number of units may be, maintain the cover 20^a against any unintentional shifting relatively to the binder.

It will be understood, if the binder includes the illustrated means for clamping 80 the units together, that a series of bolts of varying lengths is provided, so that, in order to properly clamp the units together, it is simply necessary to select the bolts of proper length in each instance. It will be 85 obvious, however, that this method of clamping the units together is merely an example and that said bolts may be replaced with other devices accomplishing the same 90 result and further, that in some cases, frictional engagement alone may be relied upon to maintain the units in proper connection with each other.

The extended bottom *a* of the form shown 95 in Fig. 1 et seq. and the horizontal portions 100 of the members 19^a and 19^c, in addition to serving as surfaces which guide the different forms of binder elements into the retaining members and avoiding the formation 105 of objectionable shoulders, also increase the strength and rigidity of the constructions.

In some cases it may be desired to seal the binder after it has been filled to capacity or to the desired extent and to thus prevent the removal of leaves 23 without detection. This may be accomplished in any desired manner; for instance, in the form first described, this result may be obtained by pasting or otherwise securing that portion of the cover 20 located between the point *b* and the scoring *c* to the retaining members 15. After this has been done, the cover 20 will hinge upon the scoring *c* and it will be impossible to remove any of the leaves 110 without detection or to add any additional leaves.

My improvement, in all of its forms, is extremely simple in construction and operation and obviates the necessity for complicated parts liable to become disarranged and disordered and at the same time provides a loose-leaf binder of maximum efficiency 115 for a variety of purposes.

Various modifications in the specific forms 120 shown and described may be made within the scope of the claims without departing from the spirit of my invention.

I claim:

1. In a loose-leaf binder, a protecting 125

- cover, a pair of members located upon said cover in spaced relation and in registry with each other, said members having recesses facing each other, a plurality of binding strips having their opposite ends removably located in the recesses of said members, and gummed flaps carried by said strips and projecting beyond an edge thereof and adapted to be connected with leaves whereby the latter are removably secured in said binder, said edge of the strips providing an abutment for an edge of the leaves whereby the latter are properly positioned relatively to said binding strips. 10
2. In a loose-leaf binder, a protecting cover, a pair of members located upon said cover in spaced relation and in registry with each other, said members having recesses facing each other, a plurality of binding strips having their opposite ends removably located in the recesses of said members, and gummed flaps carried by said strips and adapted to be connected with leaves whereby the latter are removably secured in said binder, said flaps co-operating with said members to prevent any substantial lengthwise movement of said strips in said binder. 20
3. In a loose-leaf binder, a protecting cover, a pair of recessed members located upon said cover and opening toward each other, a plurality of flexible binding strips having their opposite ends located in the recesses of said members and removable therefrom by flexing the strips, and means located on said strips for connecting them with leaves whereby the latter are removably secured in the binder. 30
4. In a loose-leaf binder, a protecting cover, a pair of recessed members located upon said cover and opening toward each other, a plurality of flexible binding strips having their opposite ends located in the recesses of said members and removable therefrom by flexing the strips, means carried by said strips for connecting them with leaves whereby the latter are removably secured in the binder, and a flexible clamping member having its opposite ends located in said recesses between and in engagement with a wall thereof and a strip whereby said strips are clamped in operative position. 40
5. In a loose-leaf binder, a protecting cover, retaining devices located upon said cover in spaced relation to each other, a plurality of strips removably connected with said devices and removable therefrom by flexing said strips, said strips being arranged for attachment to leaves whereby the latter are removably secured in said binder, and a flexible clamping member having at least one of its ends removably connected with said devices and removable therefrom by flexing said clamping member, the latter extending in engagement with the retaining devices and a strip whereby said strips are clamped against removal from said devices. 50
6. In a loose-leaf binder, a protecting cover, a pair of retaining members located upon said cover in spaced relation to each other and adapted to co-operate with binding devices to removably secure leaves in said binder, a second independent protecting cover, and means whereby said second cover is detachably connected with each of said retaining members. 60
7. In a loose-leaf binder, a pair of main retaining members connected together in spaced relation to each other, a pair of auxiliary retaining members connected together in spaced relation to each other and arranged to be superimposed upon said main retaining members, and means for detachably connecting all of said retaining members together in fixed relation to each other to form a unit. 70
8. In a loose-leaf binder, a pair of main retaining members connected together in spaced relation to each other, a pair of auxiliary retaining members connected together in spaced relation to each other and arranged to be superimposed upon said main retaining members, and co-operating flanges on said main and auxiliary retaining members whereby all of said members are detachably connected together to form a unit. 80
9. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, and flanges depending from said auxiliary members and arranged to slidably engage the flanges of said main members whereby all of said members are connected together to form a unit. 90
10. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members arranged to slidably engage the flanges of said main members whereby all of said members are connected together to form a unit. 100
11. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members arranged to slidably engage the flanges of said main members whereby all of said members are connected together to form a unit. 110
12. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members arranged to slidably engage the flanges of said main members whereby all of said members are connected together to form a unit. 120
13. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members arranged to slidably engage the flanges of said main members whereby all of said members are connected together to form a unit. 125
14. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members arranged to slidably engage the flanges of said main members whereby all of said members are connected together to form a unit. 130

unit, and bolts passing through said members whereby a relative sliding movement thereof is prevented.

11. In a loose-leaf binder, a pair of main retaining members having recesses facing each other, a connecting strip connecting said members for maintaining same in spaced relation, flanges connected with and located above said retaining members, auxiliary retaining members having recesses facing toward each other and resting upon the flanges of said main members, a connecting strip connecting said auxiliary members for maintaining same in spaced relation and located contiguously to the connecting strip of said main retaining members, flanges depending from said auxiliary members and arranged to slidably engage the flanges of said main members whereby all of said members are connected together to form a unit, bolts passing through said members whereby a relative sliding movement thereof is prevented, an independent protecting cover, and means

for detachably connecting said independent cover with said auxiliary members.

12. In a loose-leaf binder, a plurality of units each adapted to accommodate binding devices whereby leaves are removably secured in said binder, said units being located one above the other and slidably connected with each other, and means for locking said units against relative sliding movement.

13. In a loose-leaf binder, a first protecting cover, a plurality of units each adapted to accommodate binding devices whereby leaves are removably secured in said binder, said units being located one upon the other upon said cover and being slidably connected together, means for locking said units against relative sliding movement, an independent second protecting cover, and means for detachably connecting said second cover with the terminal unit to complete the binder.

In testimony whereof I have hereunto set my hand.

EDWARD ABERLE.
